Patented June 29, 1920.

UNITED STATES PATENT OFFICE.

HENRI COLOMB, OF TAVANNES, SWITZERLAND.

DOUBLE-ROLLER LEVER-ESCAPEMENT.

1,345,318.

Specification of Letters Patent. Patented June 29, 1920.

Application filed January 5, 1920. Serial No. 349,643.

To all whom it may concern:

Be it known that I, HENRI COLOMB, citizen of the Swiss Republic, residing at Tavannes, in the Canton of Berne, Switzerland, have 5 invented certain new and useful Improvements in Double-Roller Lever-Escapements, of which the following is a specification.

In double roller lever escapements hitherto manufactured, the overswinging organs 10 are constituted by the small roller and the prong. The whole is completed by the horns of the fork, which start operating, with the roller pin, when the relative position of the prong and of the notch in the small 15 roller do not afford, momentarily, any safety to the overswinging motion. As a matter of fact, the horns of the fork are appendices giving the watchmaker a certain amount of work and trouble on securing proper end- 20 shake of said horns.

Considering the ratios heretofore adopted by watch-manufacturers in the construction of double-roller lever escapements, those horns are absolutely necessary. It is generally admitted as a fact that the diameter 25 of the circumference described by the outermost point of the roller pin from the pivoting center of the roller, on the one hand, and the diameter of the small roller on the 30 other hand, should be in a ratio very close to $\frac{5}{3}$. Figure 1, in the annexed drawings, shows that the aforesaid ratio and in normal 35 conditions of construction and running, viz: for an angle of lever pallet of 12° and for a like angle of balance pallet of 40° , it is not possible, even though the diameter of the notch be reduced to a strict minimum, taking into account end-shake of pivots and defects in the manufacture, to do away with 40 the fork-horns. The hatched portions of the aforesaid figure plainly show that safe overswinging motion would no longer exist, should the horn side be finished off at right angles.

45 Fig. 1 is a plan detail of the usual type of escapement having horned forks, and

Fig. 2 is a top plan view of the improved form of the escapement.

Referring to the aforesaid Fig. 2 in which 50 is represented, so far as required for understanding the invention, a double roller lever escapement in which the angle of the lever pallet is equal to that of the ordinary escape-

ment shown in Fig. 1, the fork *a* is shown in its position as occupied when it butts 55 against the side *b* and when the roller pin *c* is about to part from the fork. The position of the notch *d* of the small roller is shown by a dotted line in the position as occupied in relation to the prong at the very moment 60 when safe overswinging motion is again secured by said prong. The figure shows that the relative position of the roller-pin, of the left inward side of the fork is such that said organs themselves prevent any overswinging motion. Horns, therefore, would be of 65 no use and have been done away with, while perfected overswinging remains unaffected.

Should we examine the conditions, due allowance being made, in which the horns may 70 be done away with, all proportions and ratios of the horns remain unchanged, as said proportions and ratios would influence the dimensions of the escape wheel and the shape of the teeth thereof, we shall notice 75 that it has been sufficient to alter, comparatively to escapements ordinarily used, the distance *O P* from the farthermost point of the roller pin to the pivoting center of the roller, at the pivoting center itself, or to 80 lengthen the ray of the small roller, or both altogether. In other words, it will be sufficient to change the proportion existing, on the one hand, between the diameter of the circumference described by the farthermost 85 point of the pin from the pivoting center of the member bearing said pin, and the diameter of the small roller, on the other hand. In the example shown, said proportion is about $\frac{4}{3}$, whereas it is $\frac{5}{3}$ in Fig. 1. This 90 alteration, though not affecting end-shake of roller and back lash of prong with said notch, permits of reducing the diameter of said notch, the result being that the spring 95 may be kept in use much longer. In the examples shown, in which the angles of the lever pallets are 12° everywhere, one has, for the escapement represented Fig. 1, a balance pallet angle of 40° , whereas, in Fig. 2, said angle is 52° . Should such enlargement be 100 considered a drawback in escapements for high grade watches, it is not so with regular commercial watches, flat watches, and watches of smaller sizes. As a matter of fact, locking rest is a defect inherent to the 105 latter styles of watches, and a purpose of

the hereinbefore mentioned enlargement of the balance pallets angle is to do away with said defect.

I claim as my invention:

- 5 1. An escapement comprising a lever having hornless forks, a prong on the lever, a balance wheel including concentrically arranged large and small rollers the smaller of which is provided with a notch, and a roller
10 pin mounted on the large roller so that the proportion existing on the one hand between the diameter of the circumference described by the farthermost point of the roller pin from the pivot center of the large roller and

the diameter of the small roller on the other 15 hand is reduced so that safe overswinging motion is secured in all positions of the balance wheel.

2. An arrangement as claimed in claim 1 wherein the proportion existing on the one 20 hand between the diameter of the circumference described by the farthermost point of the roller pin from the pivot center of the roller bearing such pin and the diameter of the small roller is inferior to $\frac{5}{3}$.
25

In testimony whereof I affix my signature.

HENRI COLOMB.
